DEVICE FOR PAPER FEED ROLLERS

José Figueira Saboia de Albuquerque,
Rio de Janeiro, Brazil

Application April 15, 1940, Serial No. 329,805

17 Claims. (Cl. 197—141)

This application is a continuation-in-part of applicant's co-pending application Serial No. 151,584, filed July 2, 1937.

This invention relates to a device for automatically locking, against further rotation and at a predetermined moment regulated at will by the operator, the paper-feed-roller or platen of a type-writing machine, tabulating machine or rollers of any other machines to which the apparatus may be applicable.

Although present day typewriters are quiet perfect, they do not however incorporate a device which will avoid the operator paying close attention to the moment when the typing reaches the bottom or near the bottom of the paper and it thus frequently happens that the written sheet is not firmly held in the typewriter at the bottom so that the last line is written obliquely. Should it be a statement that is being typewritten or tabulated, the work will often have to be repeated, as by a slight oversight, sufficient space may not have been left for the filling in of totals, etc.

The chief aim of the present invention is to afford a device for mechanically avoiding that a paper sheet which is in use in a typewriting machine, tabulating machine or the like, be unexpectedly released from the platen thus preserving a margin at the bottom of the sheet, the device being comprised of the combination of a locking mechanism, with the platen and with a reference mark situated on the carriage or on a fixed part of the machine, with which the bottom edge of the sheet will have to initially be made to coincide, and being manipulated through a special method. In this device, the essence of the invention rests in the process of relating the displacements of the bottom edge of a paper sheet, resulting from the rotation of the platen in a typewriter and the like, with the reciprocal displacements of the members of a locking mechanism operatively connectable to the platen in such a way that the platen is locked when the typing reaches a predetermined position near the sheet's bottom edge. Locking the platen warns the operator that the sheet is about to be released further typing being possible only by disengaging the locking mechanism from the platen by means of a device afforded for this purpose.

Further objects will be apparent from the following description taken in connection with the accompanying drawings in which:

Figure 1 is an exploded axial sectional view of the locking mechanism,

Figure 2 is a plan view of the guide member,

Figure 3 is a side view of the actuating screw member,

Figure 4 is an inside view of the coupling member which acts simultaneously as turning knob,

Figure 5 is a plan view of the stub shaft,

Figure 6 is an axial sectional view of the locking mechanism mounted on the platen shaft and carriage,

Figure 7 is a plan view of the locking mechanism,

Figure 8 is a cross sectional view of the locking mechanism taken on line 8—8 of Fig. 6,

Figure 9 is a plan view of a typewriter with the locking mechanism attached to the platen, and

Figure 10 is a perspective view of the ring with the reference marks thereon.

The locking mechanism, Fig. 7, according to this invention is mounted on the axle 26 of the platen 25 by means of a stub shaft 8 into which the axle 26 projects and the shaft is locked thereon against rotation by means of the set screw 23 projecting into a perforation in the axle. The shaft 8 has a circumferential groove 9 therein, a T-shaped groove 10 and a perforation 11, Fig. 5.

A cylindrical guide 2 cooperates with an actuating screw member 4 which latter is rotatably mounted on the shaft 8 and is rotatably held thereon by means of the screw or pin 12 which projects into the groove 9.

The guide 2 is secured to the carriage frame member 13 on the side face 33 of the latter by means of screws 14 passing through the flange 15 and into the member 13. A nut 1, which is threaded on the screw-threaded portion 16 of the actuating member 4, Fig. 6, holds the member 4 securely in position relative to the member 2, and turns together with the screw member.

On the end of the stub shaft 8 there is mounted a turning knob or coupling member 5 which has a part axial and a part rotary movement governed by the screw or pin 18 which projects into the T-shaped slot 10. A retaining ring 7 is held in place by means of a set screw 20 which latter projects into the perforation 11, Fig. 5, in the stub shaft 8. A spring 6 between the ring 7 and the coupling member 5 constantly urges the member 5 to the left, Fig. 6.

The locking mechanism also includes a lock ring nut 3 threaded on the screw-threaded portion 16 having a projecting pin or screw 21 which latter projects in the slot 22 in the cylindrical guide 2, Figs. 1 and 6, and is guided therein to prevent rotation of the lock ring 3 but will permit axial displacement thereof upon rotation of the actuating member 4. The lock ring nut 3 is pro-

vided with a pointer element 24 mounted thereon by means of the screw 21 and which is adapted to cooperate with a marking line or graduation 27, which last is engraved on a small detachable plate 42 which may be placed in a suitable position on the guide member and fixed thereon by means of a small screw 43.

The coupling member 5 is provided with a turning knob portion 28 and a series of circumferentially arranged perforations 29 on the inside face 30 which cooperate with the pin 17 on the side face 31 of the actuating screw member 4. The pin 18 cooperates with T-shaped slot 10 and the turning knob member 5 will rotate the platen 25 by means of the stub shaft 8 or upon rotation of the platen upon reaching the end of a line when typing, the stub shaft 8 will rotate the turning knob member 5 together with the actuating screw member 4 by means of a perforation 29 and the pin 17, when the pin 18 is in the leg groove 32. If, however, the turning knob member is pulled to the right, Fig. 6, the pin 18 reaches and cooperates with the head groove 33 which also maintains a rotary cooperation with the stub shaft 8 but the rotary connection between the member 5 and member 4 is broken since the pin 17 is not projecting in any one of the perforations 29.

The actuating screw member 4 is also provided with a ring 39 supporting a series of graduations 34 (1, 2, 3). The graduations or reference marks numbered 1, 2, 3 are so arranged and placed (the ring permits the definite fixing of said marks in one suitable position on the cylindrical surface 41) as to permit locking of the platen, if the device is used according to the instructions of this specification, at a moment when by disengaging the locking mechanism, one, two, three, etc. lines, according to whether reference 37 has been made to coincide with markings 1, 2 or 3, may still be typed upon the sheet before the precise moment when this last is released from the paper feed roller. The ring 39 is fixed in the correct position on the cylindrical surface 41 of the actuating screw member by means of a small screw 44, threaded to ring 39.

The locking mechanism consists primarily of the actuating screw member 4 and the lock ring 3 threaded thereon. Member 4 has a free rotary movement on shaft 8, whereas ring 3 will only have possible travel along the course of the screw threaded portion 16, along the longitudinal slot 22 in which the ring is guided so that upon rotation of the member 4, the ring 3 not being able to rotate at the same time, must necessarily travel along the screw threaded portion 16. When the ring 3 has travelled the full length of the portion 16, it encounters a radial abutment surface formed upon the actuating screw member, that is, the head of the actuating screw member, which is thus impeded of further movement since said screw member and lock ring at this moment form a unit and the lock ring 3 cannot, by construction, rotate. Thus the member 4 is locked against rotation, as is also the shaft 26 of the roller or platen 25 of the machine.

It is evident that the number of rotations and its fractions the member 4 can complete before becoming locked will depend on the distance of the lock ring 3 from the end of its course along the screw threaded portion 16, and this distance can be regulated at will by the operator in cooperation with a determined distance which must be covered by the bottom edge of the sheet from a mark or point 35, Fig. 9, conveniently chosen

on the carriage, to another convenient point, which may be the point where the sheet is released from the platen, that is, the point where the sheet becomes disengaged from the small guide rollers under the platen, which press the sheet against it. This is therefore the fundamental principle of the device. It is to be remarked that the purpose of the nut 1 previously cited is to connect the members 2 and 4, but it may also serve as an obstacle to the axial displacement of the lock ring 3, so that this mechanism may be adapted to lock the actuating screw member and, consequently the platen, both when the lock ring 3 encounters the head of the screw member 4 or the nut 1 placed at said screw's other extremity, or in other words, whatever the direction of displacement of said lock ring 3 along the screw member 4, or wherever the locking mechanism is placed at the right or left side of the machine carriage.

The device operates as follows:

The sheet of paper is placed in the machine in the usual manner but the bottom of the sheet is brought down by continued rotation of the platen 25 until the bottom edge of the sheet coincides with a reference or guide line 35 on the paper guide 36 of the machine, Fig. 9, any other suitable line or guide means may be used, it being immaterial as to its location provided that reference marks 34, 37 and 27 be placed conveniently to collaborate with mark 35, Fig. 9, previously selected as the initial position of the sheet's bottom edge.

The marking line 27, 37 and the lines or marks 34 (1, 2, and 3) Fig. 7, cooperate with the line 35 for the sheet's bottom edge initial position which should always be the same at the time of connecting the device. For this position of the paper, the pointer 24, indicating the position of lock ring 3, is placed in alignment with the mark 27 by turning the actuating member 4, the coupling member 5 having been previously disconnected by pulling the member 5 to the right, Fig. 6, to disengage the pin 17 from one of the perforations 29. When pointer 24 is in coincidence with mark 27, marks (1, 2, or 3) will be close to mark 37, so that the actuating member 4 is now turned slightly and one of the horizontal lines 34 (1, 2, or 3) coincides with mark 37 (Fig. 7) (dependent upon the number of additional lines, that is one or two or three, etc. it is desired to type, after the mechanical locking of the platen and subsequent manual unlocking of the same, and before the paper becomes loose from the said platen). The member 5 is now engaged with the member 4 by rotating the member 5 slightly so that the pin 17 engages in one of the perforations 29 after which the platen is turned back so that the paper is brought in position to start the first typing line, which also moves ring 3 with its pointer to the left, Fig. 7, a distance relative depending upon the length of the paper.

As the typing progresses on down the sheet of paper and upon each line spacing and return movement of the carriage of the typewriter the shaft 26 is turned slightly together with the stub shaft 8, coupling member 5, and actuating member 4 together with the threaded portion 16, the latter causing a gradual and intermittent axial movement of the ring 3 to the right since the latter is fixed against rotation due to the slot 22 and the pin 21. When the bottom edge of sheet is again in front of mark 35 (Fig. 9) the pointer will again be facing mark 27 and the lock ring 3 will be separated from the head of the screw

actuating member 4 by a distance so established that said screw will be locked, and consequently the platen, one, two, three or more lines (according to how the locking mechanism was set by the operator) before the point where the sheet is released from the platen, in as much as the bottom edge of the sheet, starting from point 35 (Fig. 9) covers a determined distance which terminates at the point where the sheet is released from the platen, this distance cooperating with the distance the ring 3 has to cover starting from the position when the pointer 24 coincides with mark 27 to that in which it encounters the head of the screw actuating member 4.

The operator is thus warned that only one, two, three, etc. lines (according to the settling of the locking device, when coupling it) can be written, when he unlocks the platen, before the sheet is released from the platen thus assuring a margin of the desired width at the bottom of the sheet. It is easily understood that markings on the actuating screw member 4 need not be limited to 1, 2, 3 but may be in greater number so that the operator will have a wider range of choice in determining the lines still to remain at his disposal. It is also clear that the device will operate with the utmost precision regardless of the length of the sheet in use or of the place where typing is commenced, conditions which are rendered immaterial to the operation of the device by the fact that markings 31, 27, 1, 2, 3 are established with regard to a determined initial position of the bottom edge of the sheet.

Thus to summarize the method of operation of the device, the knob member 5 is moved to the right and locked in the head groove 33 so that the platen may rotate freely, without causing the rotation of the screw actuating member 4 the paper is then inserted in the platen in the usual manner and the latter is turned until the bottom edge of the sheet coincides with the reference mark 35 (Fig. 9); the screw actuating member is then turned by hand until the pointer 24 is facing mark 27, then the coupling member 5 is returned to the left to its original position with a pin 17 in a perforation 29 and the pin 18 in the groove 32, the platen is rotated back to bring the paper to its first typing line thus moving the ring 3 and indicator 24 to the left. Finally when the platen cannot be rotated further when the typing is near the bottom of the sheet due to the locking of the lock ring 3, the typist will know that the typing of the sheet can progress only if he unlocks the platen. The knob 5 is now pulled to the right, Fig. 7, to unlock the platen so that one, two, three or more lines can be typed on the sheet as it was preset. It is to be remarked that the essence of this invention rests in the combination of the elements and in the process of re-latching the displacements of the bottom edge of a paper sheet resulting from the rotation of the platen in a typewriter or the like, with the reciprocal displacements of the members of a mechanism operatively connectable to the platen, and not only in the mechanical arrangement of the said mechanism which may assume any suitable disposition or form. Effectively, the combination of a determined reference on the carriage or on a fixed part of the typewriter, with which reference the bottom edge of the sheet is initially made to coincide, may be made with any form of mechanism, used for the purpose of warning that the typing of the paper sheet has reached the desired preset point.

Obviously, the present invention is not re-

stricted to the particular embodiment herein shown and described. Furthermore, the invention is capable of many variations without departing from the spirit of the invention as set forth in the appended claims.

I claim as my invention:

1. In a locking device for paper-feed-rollers supported on a carriage, a rotatable shaft supporting a paper-feed-roller and extending beyond one end thereof; a stub shaft secured coaxially to the extending end of said rotatable shaft and having a T-shaped slot near its outer end; a cylindrical guide member on said stub shaft and fixed against rotation with respect to the carriage, said guide member having a longitudinal slot therein; an indicator lock ring threaded on its inside surface and slidably axially within said guide member; a small screw in the periphery of the ring to fix said ring against rotation by cooperation with the slot in the guide member; an actuating screw member fixed against axial movement with respect to said stub shaft and rotatably mounted for adjustment on the stub shaft, said screw member having a threaded portion on its exterior to engage the threaded portion of said ring and having a pin on its outer end; and a coupling member mounted on said stub shaft near its outer end and having a series of perforations adapted to cooperate with the pin, said coupling member having a pin extending into the T-shaped slot of said stub shaft and forming a positive drive after adjustment of the actuating screw member.

2. A locking device for paper feed rollers according to claim 1, in which the coupling member and its pin are mounted for limited translational and rotational movements with respect to the stub shaft to disconnect the actuating screw member from the said stub shaft.

3. A locking device for paper-feed-rollers according to claim 1, in which the coupling member is mounted for axial movement relative to the said stub shaft and is provided with means to urge it into driving engagement with the actuating screw member, said coupling member at one end of such movement being capable of partial rotation with respect to said stub shaft and at the other end of such movement being operatively connected to the actuating screw member.

4. The combination with the platen of typewriting machines, tabulating machines and the like, and a guide mark on an unrotatable part of the machine, of an adjustable mechanism mounted on a shaft of the platen and adapted to automatically lock said platen against rotation determined by adjusting said mechanism to the guide mark with the bottom edge of the sheet to be typed over the said mark and before typing on the sheet to maintain a predetermined bottom margin on the typed sheet.

5. A locking device for the platens of typewriting machines and the like in which the machine is provided with a reference mark for the bottom edge of the sheet to be typed, comprising cooperating fixed and movable parts mounted on a platen carriage and platen respectively and the parts having reference marks thereon so that the locking mechanism may be set with respect to the bottom edge of the sheet to be typed in correspondence with the said reference mark on the machine to effect a locking of the platen against rotation when a predetermined point on the bottom of the sheet is reached after the typing operation to thus leave a predetermined bottom margin on the sheet.

6. In a device for providing a predetermined margin at the bottom of typewritten sheets in a typewriter and the like, the combination of a platen and a fixed reference mark on the typewriter, in cooperation with the platen to set the bottom edge of the sheet to be typed in alignment with said mark, and a locking mechanism connected to the platen and which is adjustable so that said mechanism can be set relative to the bottom edges of the sheet in alignment with the reference mark whereby when the sheet is typed the mechanism will lock the platen against further rotation at a predetermined moment before the bottom edge of the sheet is reached to thereby leave a predetermined margin at the bottom of the typed sheet.

7. In a device for providing a predetermined margin at the bottom of typewritten sheets in a typewriter and the like, the combination of a platen and a fixed reference mark on the typewriter, in cooperation with the platen to set the bottom edge of the sheet to be typed in alignment with said mark, a locking mechanism connected to the platen and which is adjustable so that said mechanism can be set relative to the bottom edge of the sheet in alignment with the reference mark whereby when the sheet is typed the mechanism will lock the platen against further rotation at a predetermined moment before the bottom edge of the sheet is reached to thereby leave a predetermined margin at the bottom of the typed sheet, and fixed and movable parts having reference marks thereon to permit the typing of at least one additional line on the sheet from the preset position where the mechanism actually locks the platen against rotation and before the sheet becomes loose from the platen.

8. In a device for providing a predetermined margin at the bottom of typewritten sheets in a typewriter and the like, the combination of a platen and a fixed reference mark on the typewriter, in cooperation with the platen to set the bottom edge of the sheet to be typed in alignment with said mark, a locking mechanism connected to the platen and which is adjustable so that said mechanism can be set relative to the bottom edge of the sheet in alignment with the reference mark whereby when the sheet is typed the mechanism will lock the platen against further rotation at a predetermined moment before the bottom edge of the sheet is reached to thereby leave a predetermined margin at the bottom of the typed sheet, fixed and movable parts having reference marks thereon, and a pointer cooperating with the reference mark on the fixed part to permit the typing of at least one additional line on the sheet from the preset position where the mechanism actually locks the platen against rotation and before the sheet becomes loose from the platen.

9. A locking mechanism for a platen of typewriting machines and the like to provide a predetermined bottom margin on the sheet to be typed, comprising an actuating screw member having a screw-threaded portion and rotatably mounted for adjustment on a shaft of the platen, a guide member securely mounted on a carriage of the platen and extending over the screw-threaded portion of the screw member, said guide member having a longitudinal slot therein, a lock ring engaging the screw-threaded portion and having a portion projecting into the slot, and means for coupling the actuating screw member with the platen shaft whereby when an abutment surface on the locking ring meets a cooperating

abutment surface formed upon the actuating screw member, the said lock ring will lock the platen against further rotation.

10. A locking mechanism according to claim 9, in which the means for coupling the actuating member is in the form of a turning knob for the platen which last may be coupled and uncoupled with the locking mechanism but always remains coupled with the said turning knob.

11. A locking mechanism according to claim 9, in which the actuating screw member is provided with a lateral projecting pin, and in which the coupling means is in the form of an axially adjustable turning knob slidably mounted on the shaft and having a plurality of circumferentially arranged perforations in a side face thereof to cooperate with the projecting pin in the screw member to couple the screw member with the turning knob and the platen shaft.

12. A locking mechanism for the platen of a typewriter and the like to leave a predetermined bottom margin on the sheet to be typed, comprising a stub shaft securely mounted on an axle of the platen, an actuating screw member having a screw-threaded portion and rotatably mounted for adjustment on the stub shaft, a guide member securely mounted on a carriage of the platen and extending over the screw-threaded portion of the screw member, said guide member having a longitudinal slot therein, a lock ring engaging the screw threaded portion and having a portion projecting into the slot, and a turning knob member slidably and rotatably mounted for limited movements on said stub shaft, said knob member and actuating screw member having means to couple and uncouple the actuating screw member from the stub shaft and when coupled the rotation of the platen promotes the axial displacement of the lock ring so that the platen will be locked against rotary motion when a radial abutment surface on the lock ring meets a cooperating abutment surface formed upon the actuating screw member.

13. A locking mechanism according to claim 12, in which the stub shaft is provided with a circumferential groove and a T-shaped groove, and of which the actuating screw member is provided with means projecting into the circumferential groove to permit rotary motion of the actuating screw member but prevent axial movement thereof relative to the stub shaft, and the knob member has means thereon projecting into the T-shaped groove to permit limited rotary and axial movement of the turning knob relative to the stub shaft.

14. A locking mechanism according to claim 12, in which the course of the lock ring is positively limited in either direction along the actuating screw member by its location between a radial abutment surface at one end of the screw member and a nut secured upon the opposite end of the screw-threaded portion of the screw member whereby the locking mechanism is capable of operation in either direction of rotation.

15. A locking mechanism according to claim 12, in which a ring presenting a series of numbered reference marks is adapted to the screw actuating member in such a position that the said references may cooperate with a fixed reference mark on the guiding member, and in which an adjustable plate supporting a reference cooperating with an indicator pointer on the lock ring nut is adjustable to the guide member in

such a position as to permit the cooperation of the reference with said pointer, whereby said reference marks on the ring and plate may easily be adjusted in a position cooperating with a third reference mark on a unrotatable part of the typewriter and the like, with which latter mark the bottom edge of the sheet is made to coincide at the moment of coupling the locking mechanism to the platen.

16. In a typewriter or the like having a platen with an axle, the combination with a guide mark in the path of motion of a sheet inserted into the typewriter and on a fixed portion of the typewriter, of a mechanism mounted on the axle for locking the platen against rotation, said mechanism comprising means for setting the same in adjusted position relative to the bottom edge of

5 the sheet to be typed when in register with the guide mark, and said mechanism also including means to lock the platen against further rotation after a predetermined number of revolutions of the platen when the sheet has been typed to thereby leave a predetermined preset bottom margin on the typed sheet.

10 17. A device according to claim 16, in which the two means includes a pair of non-rotatable members, and a pair of rotatable members mounted with a stub shaft securely mounted on the axle, one of said rotatable members having one of the non-rotatable members mounted thereon in axial adjustable relationship relative to each other.

15 JOSÉ FIGUEIRA SABOIA DE ALBUQUERQUE.
